FOLDING FRAME FOR SOFA BEDS

Rudolph Coopersmith, Clayton, Mo.

Application September 19, 1949, Serial No. 116,463

11 Claims. (Cl. 5—36)

1

This invention relates to folding beds or couches and is more particularly directed to the provision of a sectional frame work therefor which is pivoted together so that when folded, the sections are superimposed one on the other and may be unfolded by grasping the upper section and moving it outwardly from the folded bed, the sections pivoting on each other from the folded to unfolded position and vice versa.

The primary object of the invention is to provide a foldable mattress supporting frame so arranged that a part of a sectional mattress is disposed between two sections of the frame when folded one above the other, a third section of the frame and mattress forming a seat cushion when folded onto the other two sections.

Another object of the invention is to provide a frame for a sofa bed in which a foldable sectional mattress supporting frame is received, each section being pivoted so that the mattress frame may be unfolded and folded by a simple back-and-forth movement of the outer or upper section and in which means is provided for rigidly supporting the sections in their folded and unfolded conditions.

This invention consists in the provision of a frame for a sofa bed into which a four-section foldable mattress frame is folded, the sections being pivotally connected together so that four sections will fold and unfold one above the other by moving the upper or outermost section toward or away from the frame. The invention also consists in the provision of supporting means for the unpivoted ends of each section for furnishing support for the several sections when in folded condition.

In the drawings:

Fig. 1 is a plan view of the unfolded mattress and sofa bed frame,

Fig. 2 is a side elevational view thereof,

Fig. 3 is a sectional view taken along the line 3—3 of Fig. 2,

Fig. 4 is a sectional view taken along the line 4—4 of Fig. 2,

Fig. 5 is a sectional view taken along the line 5—5 of Fig. 2,

Fig. 6 is a sectional view taken along the line 6—6 of Fig. 2,

Fig. 7 is a side elevational view similar to Fig. 2 but with the mattress frame partly folded,

Fig. 8 is another side elevational view of the partly folded frame,

Fig. 9 is a side elevational view of the folded frame,

Fig. 10 is a sectional view taken along the line 10—10 of Fig. 9,

2

Fig. 11 is a perspective view of the mattress used on the improved mattress frame,

Fig. 12 is a plan view of a modified form of the invention,

Fig. 13 is a side elevational view thereof,

Fig. 14 is a front elevational view thereof,

Fig. 15 is a sectional view taken along the line 15—15 of Fig. 13,

Fig. 16 is a side view of the modified mattress frame showing the position of the parts after the first folding operation,

Fig. 17 is a side view of the modified mattress frame showing the position of the parts in the second folding operation,

Fig. 18 is a side elevational view showing the folded mattress frame; and

Fig. 19 is an enlarged side elevational view of a portion of the mattress frame.

This invention is embodied in a frame structure illustrated in the several views of the drawings in which the numeral 1 designates a pair of horizontal bars, and 2 and 3 are supporting legs secured to bars 1, the point of securement of the ends of the bars being near the lower ends of legs

20 2 and 3. Braces 4 are provided between bars 1 and each of legs 2 and 3 for reinforcing the frame. The legs 2 have rigid horizontal mattress frame supporting bars 5 secured thereto which cooperate with parts of the folding mattress frame.

25 30 At the upper end of each of the legs 3 is pivotally secured at T-member 6, each of the T-members comprising a vertical bar 7 and a cross bar 8 much longer than the vertical bar 7, the lower end of each bar 7 being pivoted to the upper ends of each of the legs 3. A lever 9 is pivoted to each of the bars 1 by means of a pin 10 and each is slidably associated with bars 11 in slots 13 cut therein in which a pin 14 slides, the pin being secured to lever 9. Each bar 11 is pivoted to one end of each of the cross-bars 8 by means of a pin 15. The unpivoted ends of bars 11 are connected by means of a bar 16 disposed parallel to bar 17 connected between the legs 2. The cross-bars 8 of the T-members are connected by a bar 18 parallel to bars 16 and 17. Reinforcing members 19 are connected between the outer ends of the cross-bars 8 and bar 18 for increasing the rigidity of bar 18. Bars 20 are pivotally secured to levers 9 near pins 10 and are also pivoted to the upper end of vertical bars 7 about the pin connecting it to cross-bar 8. Bars 20 move levers 9 relative to bars 11 in slots 13 during the folding operation of the mattress frame. The bars 11, 16 and 18 constitute one section 35 40 45 50 55 of the foldable frame. The cross-bars 8 and

the bar 18 constitute the second section of the foldable bed frame.

The third section of the foldable bed frame comprises bars 21, one end of each bar being pivoted to cross-bars 8 by means of pins 22. Bars 23 are pivoted to bars 21 by means of pins 24. Bars 25 are provided at one end with a right angular portion 26 and are pivoted to bars 21 by means of pins 27 moving in slots 27' cut in bars 21. The right angular portion 26 of the bars is connected to the upper ends of legs 3 by the pin which connect the T-member 6 thereto. Bars 21 have angle members 28 and 28' secured thereto whose functions will be subsequently described in connection with the folding and unfolding operation of the frame. The right angular portion 26 of each of the bars 25 is provided with a perforation in which a pin 29 is positioned about which link 30 pivots. Each of the bars 1 has a link 31 secured thereon by means of a pivot pin 32. A spring 33 is connected between each of links 30 and 31 on each side of the bed frame for facilitating the folding and unfolding thereof.

The fourth section of the frame comprises bars 34 which are pivoted to the plate members 35 secured to the outer end of bars 21. A bar 36 parallel to bars 16, 17 and 18 is connected between bars 34, thereby completing the bed frame. Corner braces 37 are provided for reinforcing the frame. The outer ends of the third section are supported by legs 38 suitably secured to plate members 35. A pair of legs 39 is secured to bars 36 for supporting the fourth section of the bed frame. These legs support the fourth section of the mattress supporting frame in the folded and unfolded condition thereof. Bars 40 are pivoted to bars 23 by means of pins 41 and are pivoted to bars 34 by means of pins 42. The lower ends of the bars 23 are connected by a bar 43 suitably braced by straps 44 connected between bars 23 and 43. A bar 45 is connected between the legs 3 and constitutes a base for legs 39 when the mattress frame is in folded condition.

The bed frame is folded and unfolded by lifting the bar 36 upwardly and simultaneously moving toward or away from the stationary bar members 1 and 5 and legs 2 and 3 forming part of the sofa frame. The lifting and pushing action on bar 36 will cause bar member 34 to pivot about the pins in plate member 35. The bar members 21 will pivot about pins 22, and the T-member 6 will pivot about the pins in the upper end of legs 3; the legs 38 will move toward bars 21 under the influence of bars 34 and 36. The bar members 11 will pivot about pins 15 while pins 14 will slide in slots 13 and lever 9 will pivot about pins 10. The several sections and members will assume the positions shown in Fig. 9 and upon completion of the folding operation the bars 11 and 16 will lie in a plane substantially parallel to the plane of bars 1. The springs 33 will now be slack, having been tensioned in the unfolded position so that their force is utilized in folding the mattress frame. The bars 21 will occupy a position directly above bars 11 and the angle members 28 will rest on the horizontal bars 5. The bars 34 will be positioned above members 21 with legs 38 and bars 40 resting on angle members 28. The legs 39 will rest on bar 45, thereby providing a rigid support for the mattress frame when folded into a sofa.

A mattress supporting fabric 46 is suspended from bars 17, 11, 8, 21, 34 and 36 in the conventional manner. A mattress 47, which is made up in two sections connected by a flexible member

48, is supported on the fabric 46. The portion of the mattress resting on the section of the fabric suspended from bars 11, 16, 8 and 21 is folded so as to be positioned between bars 8, 11, and 21. The section of the mattress resting on the fabric suspended from bars 34 and 36 constitutes a base for the seat cushions of the sofa. This portion of the mattress is somewhat wider than the foldable portion so that it will completely fill the space between the sides of the sofa frame in which the bed frame is to be installed, thereby forming a more substantial base for the sofa cushions to be placed thereon when the bed frame is folded into the sofa frame.

A modified form of the invention is illustrated in Figs. 13-19 in which the numeral 49 designates the fixed horizontal bars of the stationary portion of the sofa bed frame, this portion being installed in the upholstery supporting frame of the sofa. A pair of legs 50 is secured to one end of the bars 49, the point of securement being adjacent to the lower end thereof. A second pair of legs is secured to the other end of bars 49 near the lower end thereof and extend upwardly a lesser distance than do the legs 50. A short rigid horizontal bar 52 is secured to each of the legs 50 at the upper end thereof. Suitable corner braces 53 are provided between legs 50, 51 and bars 49 for reinforcing this portion of the sofa frame and making it more rigid. The legs 50 are also connected by a bar 54 which maintains the desired lateral spacing of bars 49. A bar 55, located at the opposite ends of bars 49 from bar 54, also maintains the lateral spacing of the bars 49. This bar has an additional function which will be hereinafter set forth.

The mattress supporting frame is made up in four sections, the first of which consists of bars 56, one end of each being connected by a bar 57. Each of the bars 56 has a slot 58 cut therein, in each of which a pin 59 is received that is secured to one end of a lever 60 whose other end is pivotally secured to bar 49 by a pin 61.

The second section of the mattress frame consists of T-members 62 each comprising a vertical member 63 to which a cross-bar 64 is rigidly secured. A transverse bar 65 is connected between the vertical members 63. Suitable corner braces 66 are provided between the cross-bar 64 and the vertical member 63 for forming the second section into a rigid construction. The lower end of each vertical member 63 is pivoted to the upper end of legs 51 by pins 67, thereby enabling the second section to pivot as a unit relative to legs 51.

The first and second sections of the mattress supporting frame are pivoted together, this being accomplished by having a pin 68 connected between bars 56 and cross-bars 64. A pair of levers 69 is also connected between the two sections, one end of each bar being pivotally connected to levers 60 and the other end pivotally connected to the pin securing the two members of each T-section together. The levers 69 move the first section vertically by means of pin 69 and slot 58 connection when the frame is folded and unfolded.

The third section of the mattress supporting frame consists of bars 70, one end of each bar being pivotally connected to each cross-bar 64 by means of a pin 71.

The fourth section of the mattress supporting frame consists of bars 72, one end of each bar being pivoted to the other end of each of the bars 70 by means of pins 73 and the other ends of bars 72 connected by a transverse bar 74.

parallel to bar 54. The bars 70, at the point where pins 73 are connected thereto, have a plate 70' fastened therein, thus facilitating the pivotal motion. Legs 75 are pivoted to pins 73 and connected together by a transverse bar 76 so that they move as a unit. Braces 77 are provided which extend between legs 75 and transverse bar 76 for increasing the rigidity thereof. Mattress protecting members 78 for the joint between the third and fourth sections are pivoted to bars 72 by means of pins 78' and rest on extensions 75' of legs 75, said extensions located between the adjoining ends of bars 70 and 72 (Fig. 19), both supported by legs 75. The folding of the two sections is facilitated by a U-shaped lever 80 pivoted to bars 72 on pins 78'. The U-shaped member 80 has levers 81 pivoted thereto by means of pins 82 and said levers are also pivoted to bars 70 by means of pins 83. A spring 84 is connected between one end of lever 81 and angle support 89 which reacts on the lever 80 for assisting in the actuation of the third and fourth sections during the folding operation. The outer ends of bars 72 and bar 74 are supported on legs 85 secured to bar 74 and held rigid by braces 86 (one not shown). A mattress stop 87 is secured to bar 54 that holds the mattress in position on the frame during the folding and unfolding thereof. The bars 70 have angle supports 88 and 89 secured thereto whose function will be hereinafter set forth.

The mattress support comprises the four sections described consisting of bars 54, 49 T-section 62, and bars 70, 72 and bar 74. A wire fabric 90 is suspended from these several bars by means of springs 91 and suitable braces 92 are provided at the corners and between the transverse bars and some of the side bars for the purpose of stiffening the frame.

Assuming the frame to be unfolded as shown in Fig. 13, the bar 74 is lifted until the third and fourth sections are in the vertical position shown in Fig. 16, the two sections pivoting about pins 71. The fourth section is then pivoted about pins 73 as shown in Fig. 17, so that the leg assembly 75 is folded substantially parallel to bars 70. The leg 75 folds because bars 72 are angle bars whose upper flange at the left end portion, as viewed in Fig. 13, is cut away so that said ends of bars 72 act thereon, thereby causing them to move with the fourth frame section. During unfolding operations, the reverse action occurs aided by the mattress protector 78 and the plate 70'. Spring 84 is tensioned by the relative movement of the U-shaped lever 80, levers 81 and bars 70 and 72 which aids in counterbalancing the mattress on the frame. The fourth section folds onto the third section, each being supported at one end on angle supports 88, the opposite end thereof being supported on bars 52 by angle supports 89. If for any reason the legs 85 should not rest squarely on bar 55, the angle support 88 in conjunction with cross-bar 64, will provide support therefor. When the third and fourth sections are pivoted about pin 73, the T-sections will start pivoting about pins 67. Levers 69 force lever 60 and its pin to move relative to slot 58 so that when the folding operation is completed, as shown in Fig. 18, bars 56 lie in the plane of bars 49 and legs 85 are supported on transverse bar 55, thereby providing a rigid support for the bar 74 and forming a rigid forward upper edge for the sofa. The mattress frame is unfolded by reversing the motions just described.

A sectional mattress similar to that shown in Fig. 12 is applied to the fabric 90. The members 78 cover the joint between the third and fourth mattress supporting frame sections. When these sections fold, said members prevent the mattress fabric being pinched between the ends of the bar members 70, 72 and legs 75.

What I claim is:

1. A folding sofa bed comprising a stationary frame, a mattress supporting frame section supported for vertical movement in said stationary frame, a second mattress supporting frame section pivotally connected to said frame section and to said stationary frame, a third mattress supporting frame section pivotally connected to said second frame section and foldable to a position above said first mentioned frame section; and a fourth mattress supporting frame section pivoted to said third frame section and foldable onto said third frame section and forming a support for seat cushions.

2. A folding sofa bed comprising a stationary frame, a mattress supporting frame section, means supporting said frame section for vertical movement with respect to said stationary frame, a second mattress supporting frame section pivotally connected to said frame and to said frame section, a third mattress supporting frame section pivotally connected to said second mattress frame section and foldable to a position above said frame section, a fourth mattress supporting frame section pivotally connected to said third mattress frame section; and a sectional mattress on said mattress supporting frame section, one section foldable between said frame section, said second, and third frame sections, the other section of said mattress disposed upon said fourth frame section and forming a support for sofa cushions when said frame and mattress are folded.

3. A folding sofa bed comprising a frame, a mattress supporting frame section in said stationary frame, means supporting said frame section for vertical movement, a second mattress supporting frame section pivotally connected to said frame section and to said frame, a third mattress supporting frame section one end thereof being pivoted to said second frame section and foldable to a position above said frame section, means for supporting the other end of said third frame section when it is folded or unfolded, a fourth mattress supporting frame section having one end pivoted to the other end of said third frame section; and means for supporting the other end of said fourth frame section when it is folded or unfolded, said fourth frame section when folded to a position above said third frame section constituting a support for sofa seat cushions.

4. A folding sofa bed comprising a stationary frame, a mattress supporting frame section, means supporting said frame section for vertical movement in said stationary frame, a second mattress supporting frame section pivoted to one side of said frame section and to said stationary frame, a third mattress supporting frame section having one side pivoted to said second frame section and foldable to a position above said first mentioned frame section, a fourth mattress supporting frame section having one side pivoted to the other side of said third frame section, the other side of said fourth frame section being foldable to a position above said third frame section, means for supporting the other side of said third frame section when folded above said first

mentioned frame section, means for supporting the other side of said third frame section when it is unfolded; and means for supporting the other side of said fourth mattress frame section when it is folded and unfolded, said means engageable with said stationary frame when said third frame section has been folded to a position above said third section.

5. A folding sofa bed comprising a stationary frame, bar members on each side of said frame and secured to the ends thereof, a mattress supporting frame section forming part of a foldable supporting frame vertically movable in said stationary frame, means supporting said section for vertical movement, a T member constituting the second section of the mattress supporting frame and pivoted to said stationary frame, one side of said T member being pivoted to said first mentioned mattress supporting frame section, means connected between said stationary frame, said first mentioned mattress supporting frame section, and said T member for vertically moving said first mentioned mattress supporting frame section when said T member is pivoted, a third mattress supporting frame, one side of which is pivoted to the other side of said T member and foldable into position in said first mentioned mattress supporting section, a fourth mattress supporting frame section, one side of which is pivoted to the other side of said third mentioned mattress frame section for supporting said third frame section when unfolded, means for supporting said fourth frame section when unfolded, means on said third frame section engageable with said bar members when folded over said first mentioned frame section, means on said third frame section and on said stationary frame for supporting said fourth frame section when folded in a position above said third frame section; and means for counterbalancing said third and fourth frame sections during the folding and unfolding of the mattress frame supporting section.

6. A folding sofa bed comprising a stationary frame, a pair of supporting bars located on one side of said stationary frame and secured to the ends thereof, a mattress supporting frame consisting of a plurality of foldable frame sections, a frame section thereof capable of vertical movement in said stationary frame, means supporting said frame section for vertical movement, a T member pivoted to said stationary frame and constituting the second section of said frame, one side thereof pivoted to said frame section, a third section for said mattress supporting frame, one side thereof being pivoted to the other side of said T member and foldable into a position above said first mentioned section, a fourth section for said mattress supporting frame, one side thereof being pivoted to the other side of said third section and foldable to a position above said third frame section, means connected between said first mentioned frame section, said T member, and said stationary frame member for vertically moving said first mentioned frame section when said T member is pivoted on said stationary frame, means for supporting the other side of said third section when unfolded, means for holding said supporting means rigid and for causing it to fold against said third frame section when said third and fourth frame sections are folded, means for supporting said fourth section when unfolded, means on said third frame section engageable with said bar members when folded in a position above said first mentioned section, means on said third section and on said stationary frame for

supporting said fourth section when folded in a position above said third section; and means for counterbalancing said third and fourth sections during the folding and unfolding of the mattress supporting frame.

7. A folding sofa bed comprising a stationary frame, a mattress supporting frame section disposed within said stationary frame, means supporting said frame section for vertical movement, a T member constituting the second mattress supporting frame section pivoted to said stationary frame, one side of said T section being pivoted to said frame section, means connected between said T member and said frame section for causing said frame section to move vertically when said T member is pivoted relative to said stationary frame, a third mattress supporting frame section, one side of which is pivoted to said T member on the side opposite to which the frame section is pivoted thereto, a fourth mattress supporting frame section, one side of which is pivoted to the other side of said third frame section, means for supporting the other side of said third frame section when in unfolded position, means for supporting the other side of said fourth section when in unfolded position, means on said stationary frame for supporting said third section in folded position, means engageable with said last mentioned means on said stationary frame for supporting the other side of said fourth section when in folded position; and means connected between said T member and said third section for counterbalancing said third and fourth frame sections.

8. A folding sofa bed comprising a stationary frame, a mattress supporting frame section disposed within said stationary frame and vertically movable therein, a pair of T-members constituting the second section of said mattress supporting frame and pivoted to one side of said stationary frame and pivoted to said frame section, a third mattress supporting frame section pivoted to the other side of said T-members, means for supporting the unpivoted ends of said third section, a fourth mattress supporting frame section pivoted to said third section, means for supporting the unpivoted ends of said fourth section, a sectional mattress disposed on said frame, one section thereof resting on said T-members and on said first and third mentioned sections, and the other section of the mattress resting on said fourth mattress supporting frame section, said mattress supporting frame when folded placing the first mentioned section of said mattress between the superposed second and third sections and the other section remaining on said fourth section and forming a support for seat cushions.

9. A folding sofa bed comprising a stationary frame, a mattress supporting frame section disposed within and vertically movable in said stationary frame, a pair of T-members constituting the second section of said mattress supporting frame pivoted to one side of said stationary frame and one side thereof pivoted to said frame section, a third mattress supporting frame section pivoted to the other side of said T-members, means for supporting the ends of said third section remote from said T-members, a fourth mattress supporting frame section pivoted to said third section, means for supporting the outermost ends of said fourth section, means on said stationary frame for supporting the end of said third section remote from said T-members when folded to a position above said second section; and means on said stationary frame on which the

fourth section supporting means rests when it is folded to a position above said third section for providing a rigid support for the outermost end of said fourth section, a sectional mattress disposed on said frame, one section thereof resting on said T-members, said second and third sections and the other section of the mattress resting on said fourth section, said mattress supporting frame when folded folding the first mentioned section of said mattress between the superposed second and third sections and the other section remaining on said fourth section and forming a support for seat cushions.

10. A folding sofa bed comprising a stationary frame, a pair of T-members pivoted to said stationary frame and constituting a section of a foldable mattress supporting frame, a second section of said mattress frame pivoted to said T-members, a third section of said mattress frame pivoted to said T-members, a fourth section of said mattress frame pivoted to said third section, means for supporting said fourth section in the unfolded condition of said mattress frame, means on said stationary frame engageable with said fourth section supporting means for supporting the fourth section when folded, a leg assembly for supporting said third section and having a portion extending between said third and fourth sections; and means for causing said leg assembly to fold and unfold between said third and fourth sections when the mattress supporting frame is folded or unfolded.

11. A folding sofa bed comprising a stationary frame, a pair of T-members pivoted to said stationary frame and constituting a section of a fold-

able mattress supporting frame, a second section of said mattress frame pivoted to said T-members, a third section of said mattress frame pivoted to said T-members including a pair of bar members, a fourth section of said mattress frame pivoted to said third section including a pair of bar members, pins for pivotally securing the bar members of each section together, means for supporting said fourth section when said mattress frame is unfolded, means on said stationary frame engageable with said fourth section supporting means for supporting the fourth section when folded, a supporting assembly for said third section including a pair of legs, one disposed on each side of said mattress supporting frame, each leg having an extension for positioning between the adjoining ends of said pivotally connected bar members, each leg pivoted to one of said pins; and means for covering said adjoining ends of said bar members and said extensions.

RUDOLPH COOPERSMITH.
